6 Claims. (Cl. 101—79)

Apparatus for printing articles with a serial number are well known, such apparatus including means for increasing the serial number, printed in one printing operation, by one digit for the next printing operation.

It is an object of the present invention to provide an improved apparatus for effecting the printing of serial numbers on, for example, data bearing media such as perforated tapes and the like used in teleprinter and data processing systems. Such apparatus being sometimes associated with a system which operates the apparatus by a single electrical current signal to print a serial number on the tape and to increase the serial number by one digit for a succeeding printing operation.

According to one aspect of the present invention, therefore, there is provided apparatus for printing a serial number on data bearing media including a plurality of type-wheels arranged in a row; means for setting one or more of the type-wheels to positions indicative of a serial number to be printed; a printing hammer for striking a data bearing medium in such a manner as to move the said medium toward the said type-wheels; an inking-tape disposed between said medium to be printed on and said type-wheels so that the serial number set up thereon is printed on the said medium; a solenoid means for operating said type-wheel setting means and said printing hammer; and a latch for retaining said printing hammer inoperative until said setting of said type-wheels, to indicate the serial number, has been effected.

According to another aspect of the present invention there is provided apparatus for printing a serial number on data bearing media including a row of type-wheels each having a series of raised numerals disposed around its periphery; ratchet and pawl arrangements for said type-wheels operative to set one or more of the said type-wheels to positions to indicate a serial number to be printed on a data bearing medium; a bar for operating said ratchet and pawl means; a lever engaging said bar; a solenoid means operative by an electric current signal to cause said setting of the type-wheels by said lever, said bar, and said ratchet and pawl arrangements; a printing hammer assembly including a hammerhead and spring means for causing said assembly to move with respect to said lever on termination of said setting of the type-wheels; an inking-tape between said hammer-head and said type-wheels; and latching means for engaging and retaining said hammer assembly at rest during said setting operation and operative thereafter by said lever to disengage itself from the hammer assembly, said hammer assembly then moving under the influence of said spring means so that the head thereof effects printing of the serial number on a data bearing medium by moving the said medium into contact with the inking medium and the inking medium into contact with said row of raised numerals indicative of the said serial number.

An embodiment of the invention is now to be described with reference to the accompanying drawings in which:

FIG. 1 is a side elevation of the apparatus; and

FIGS. 2 and 3 are respectively end and side elevations of type-wheels with respect to an inking ribbon and a tape.

Referring in the first instance to FIG. 1, a number of type-wheels 1, for example three, representing units, tens,

2

and hundreds respectively, are mounted in a row on a common spindle 3. Each type-wheel, has a series of raised numeral types equispaced around the periphery, the series ranging from 0 to 9. For each type-wheel 1 there is incorporated a ratchet-wheel 4 which is arranged to effect movement of the type-wheel through one digit position at appropriate times. For example, the "units" type-wheel will move through one digit position for each movement of its ratchet-wheel 4 through one tooth position, whilst the "tens" type-wheel will move through one digit position for each movement of its ratchet-wheel, such as 4, through ten digit positions, etc.

The mechanisms for effecting these movements of the type-wheels by their respective ratchet-wheels is well known and need not be described herein. Each ratchet wheel, such as 4, has an associated pawl, such as 17, for effecting the movements, and the pawl is mounted on a pawl arm, such as 5, pivotally accommodated on the common spindle 3. The pawl arms, such as 5, are interconnected by a connecting bar 6 affixed to each of the arms.

Pivotedly mounted on a spindle 7 there is a hammer assembly comprising a hammer stock 8 having affixed thereto a spring blade 10 and a hammer-head 22 constituted by a rubber block affixed to the free end of the spring blade. The hammer-head 22 is arranged with respect to the type-wheels, such as 4, so that when a printing operation takes place, the lower face of the hammer-head 22 is caused to engage with a tape T which in turn engages an inking ribbon 21, and the inking ribbon engages with a row of raised numerals, representative of a serial number, on the type-wheels. FIGS. 2 and 3 show respectively end and side views of the dispositions of the type-wheels 1 with respect to the hammer-head 22, the tape T and the inking ribbon 21.

The inking ribbon 21 is wound on spools 23 and 24 and fed from one spool onto another by way of pulleys, such as 25, and by a well-known type of mechanical linkage between the spools and an operating lever 9.

The operating lever 9 is also pivotally mounted on spindle 7 and has a forked portion at its free end which is arranged to engage the bar 6. An abutment screw 11 engages in a tapped hole in the hammer stock 8 and is rotatable therein to permit adjustment of its position, so that relative displacement may be maintained between the hammer stock 8 and the operating lever 9 which are biased toward each other by a tension spring 12 affixed at its ends to pins 26 and 27 extending respectively from the hammer stock and operating lever. A tension spring 19 is affixed at one of its ends to a pin 28 extending from the operating lever 9 and at its other end to a pin 29 in the apparatus frame (not shown).

The plunger 30 of a solenoid 31 is pivotally connected to the operating lever 9 by a link member, such as 18. An L-shaped latch 13 is pivotally mounted at the juncture of its two legs on a pin 14 affixed to the apparatus frame (not shown). The longer upper leg of the latch is step-like in form and is arranged to be biased into engagement with the free end of the hammer stock 8 by a tension spring 16 affixed to the latch 13 and to a pin 32 extending from the apparatus frame (not shown). A pin 15 extends from the side of the operating lever 9 and is arranged to engage the shorter leg of the latch 13. A stop pin 20, affixed to the apparatus frame (not shown), is arranged to be engaged by the operating lever 9 to permit only limited pivoting movement thereof in a clockwise direction under the influence of the tension spring 19.

Operation of the apparatus is now to be described with reference to FIG. 1. The tape T is passed between the hammer-head 22 and the inking-ribbon 21; and at an appropriate time, when it is desired to apply a serial number to the tape, the solenoid 31 is energised by an electric current signal and the plunger 30 is drawn into the core

by magnetic attraction. Through the link member 18, the operating lever 9 is caused to pivot in an anticlockwise direction about the axis of spindle 7 against the influence of tension spring 19.

Whilst this pivoting movement of operating lever 9 is taking place, the hammer stock 8, and in consequence the spring blade 10 and the hammer-head 22, are held from movement with the operating lever 9, under the action of the tension spring 12, by latch 13, the stepped portion of which is in engagement with the free end of the hammer stock 8.

Movement of the operating lever 9 with respect to the hammer stock 8 causes an increase in the tension of spring 12 disposed therebetween. This pivoting movement of operating lever 9 causes connecting bar 6, engaged by the forked end of operating lever 9, to pivot the pawl-arms, such as 5, in a clockwise direction about the axis of spindle 3. The pivoting action of the pawl-arms 5, in turn, cause pawls, such as 17 to rotate ratchet-wheels, such as 4, in a clockwise direction through one tooth position. One or more type-wheels, such as 1, are then moved through one digit position by well-known means to indicate the next aerial number to be printed.

Directly after the movement of the type-wheel or type-wheels has been effected, the operating lever 9, in its pivoting movement, reaches a position in which the pin 15, extending therefrom, engages the short leg of the latch 13 and causes the latch to pivot about the axis of pin 14 in an anticlockwise direction. This pivoting action of the latch 13 withdraws the stepped longer leg thereof out of engagement with the free end of the hammer stock 8. The hammer stock 8, spring blade 10, and the hammer-head 22 are therefore permitted to pivot in an anticlockwise direction under the influence of tension spring 12.

During this pivoting movement, the abutment screw 11 in the hammer stock 8 engages with the operating lever 9 to arrest movement of the hammer stock 8 with the hammer 22 spaced from the tape, as shown in FIG. 1. However, the inertia of spring blade 10 and the hammer-head 22 causes the blade to bend about a point where the blade separates from engagement with the hammer stock 8. This bending action continues and permits the hammer-head 22 to engage the tape T, to bring it into engagement with the inking-ribbon 21, and the inking-ribbon in turn into engagement with the raised numerals of the type-wheels, such as 4, thus effecting printing of the serial number on the tape. The hammer-head 22 is then immediately lifted out of engagement with the tape under the action of the spring blade 10 taking up its normal position with respect to the hammer stock 8.

On termination of the electrical signal pulse, the operating lever 9 is permitted to move about its pivot back to its original position under the influence of tension spring 19, taking with it the hammer stock 8, and in consequence the spring blade 10 and the hammer-head 22.

The latch 13 is re-set to its original position when the end of the hammer stock 8 again comes into a position in which it can be engaged by the stepped end of the latch 13; and the pawl-arm, such as 5, and the pawls such as 17, thereon are pivoted in an anticlockwise direction under the action of connecting bar 6 to bring the pawls into engagement with succeeding teeth of the ratchet-wheels prior to the next printing operation.

It is to be understood that the foregoing description of specific examples of this invention is not to be considered as a limitation on its scope.

What I claim is:

1. Apparatus for printing a sequence of serial numbers comprising a plurality of types representing numerals; means for arranging said types to represent a serial number; step-by-step type setting means for rearranging said types at each step to represent a succession of serial numbers; an operating lever mounted for limited movement in a predetermined path; means for normally urg-

ing said lever towards a position of rest; means operatively connecting said lever to said type setting means, whereby movement of said lever in a predetermined direction away from said position of rest will cause one step in said type setting means to rearrange said types to represent the next successive serial number; means comprising a print hammer mounted for movement towards and away from said types and arranged to cause printing of the serial number to which said types have been set on a data bearing medium supported adjacent said types when said hammer reaches the limit of its movement towards said types; means operatively connecting said lever and said hammer for storing energy when said hammer remains at the limit of its movement away from said types and said lever is moved in said predetermined direction to rearrange said types; latch means for holding said hammer at the limit of its movement away from said types when said lever is so moved; means on said lever for releasing said latch means when said lever has reached the end of its movement in said predetermined direction and said types have been rearranged to represent the next successive serial number, whereby said hammer will move under the action of said energy storing means towards said types and printing of said serial number will be effected; and means for moving said lever in said predetermined direction.

2. Apparatus for printing a sequence of serial numbers comprising a plurality of types arranged in a row to represent a serial number; step-by-step type setting means adapted at each operation thereof to rearrange said types to represent the next succeeding serial number; a print hammer mounted for movement towards and away from said types and adapted to cause printing of the number set up on said types when said hammer reaches the limit of its movement towards said types; single operating means mounted for limited movement in a predetermined path; means for normally holding said operating means at a position of rest at one limit of its movement; means connecting said operating means with said type setting means for causing operation thereof when said operating means is moved in a predetermined direction in said path; stop means on said operating means adapted to engage said print hammer for establishing the rest position of said print hammer when said operating means is in its rest position and the other limit of movement of said print hammer when said operating means is at the other limit of its movement; means connecting said operating means with said print hammer for storing energy when said print hammer is held in its rest position and said operating means is moved in said predetermined direction; latch means for holding said print hammer in its rest position when said operating means is so moved; and means on said operating means for releasing said latch means when said operating means has reached the limit of its movement in said predetermined direction, whereby said print hammer is urged towards said types by said energy storing means until it is stopped by said stop means.

3. Apparatus, according to claim 2, further comprising means for adjusting the relative position of the print hammer and the stop means to adjust thereby the limits of movement of said print hammer.

4. A printing mechanism comprising an operating lever having a given rest position and adapted to have limited movement in a given path; a print hammer unit also mounted for limited movement in a given path; resilient coupling means between said unit and said lever and adapted to store energy when relative movement in a given sense occurs between said lever and said print hammer unit; a movable latch member normally positioned to prevent movement of said print hammer unit when relative movement in said given sense occurs by displacement of said operating lever from said rest position; printing mechanism adapted to be operated by said hammer-unit; a latch release member extending from said operating lever at a given point thereon for releasing said latch.

member only after said lever has undergone a predetermined displacement in said given sense from said given rest position to permit said print hammer unit to be moved into operative relation with said printing mechanism; and means for moving said operating lever out of said rest position to produce relative movement in said given sense between said print hammer unit and said lever.

5. A mechanism, according to claim 4, including means operatively coupled to said operating lever for varying the indication to be printed by said mechanism during said predetermined displacement of said arm from said given rest position.

6. A mechanism, according to claim 5, wherein said hammer unit includes a hammer stock, the resilient coupling means being between said stock and said operating lever; a hammer head, and a leaf-spring member connecting said hammer head to said stock for inertially im-

parting a whip-like movement to said head in association with an abrupt deceleration of said stock; said mechanism further including means for abruptly interrupting the movement of said hammer stock, before said hammer head reaches its final printing position, following release of said latch member, to thereby impart said whip-like movement of said hammer-head.
